CLAIM

The ornamental design for an audio listening system, as shown and described.

DESCRIPTION

FIG. 1 is a perspective view of an audio listening system showing our design;

FIG. 2 is a front view thereof;

FIG. 3 is a rear view thereof;

FIG. 4 is a top view thereof;

FIG. 5 is a bottom view thereof; and,

FIG. 6 is a right side view thereof.

The broken lines in the figures show portions of the audio listening system that form no part of the claimed design.
